END PLATE FOR AN ILLUMINABLE SIGN

Fred Iglesias, Chicago, Ill.

Application January 12, 1949, Serial No. 204

Term of patent 14 years

(Cl. D1—4)

To all whom it may concern:

Be it known that I, Fred Iglesias, a citizen of the United States, residing at Chicago, in the county of Cook and State of Illinois, have invented a new, original, and ornamental Design for an End Plate for an Illuminable Sign, of which the following is a specification, reference being had to the accompanying drawing, forming part thereof.

Fig. 1 is a side elevational view of an end plate for an illuminable sign, showing my design.

Fig. 2 is an end elevational view; and

Fig. 3 is a top plan view thereof.

I claim:

The ornamental design for an end plate for an illuminable sign, as shown.

FRED IGLESIAS.
